UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

LASTING-MACHINE SPEED-CONTROLLING MECHANISM.

1,072,694.

Specification of Letters Patent.

Patented Sept. 9, 1913.

Application filed August 3, 1912. Serial No. 713,132.

To all whom it may concern:

Be it known that I, MATTHIAS BROCK, a citizen of the United States, residing at Boston, in the county of Suffolk and State 5 of Massachusetts, have invented certain Improvements in Lasting-Machine Speed-Controlling Mechanism, of which the following description, in connection with the accompanying drawings, is a specification, like reference characters on the drawings indicating like parts in the several figures.

This invention relates to certain improvements in speed controlling mechanisms for shoe machines and is herein shown as embodied in that form of novel controlling mechanisms for lasting machines described in British Patent No. 3516/11. In that mechanism and others of which that is typical driving mechanism is caused to actuate 20 operating tools at one or another speed according to the position to which a treadle is depressed. In the use of this particular lasting machine the operator holds the shoe in his hands for the action of the gripper and tack 25 driver upon it and this presentation of the shoe requires skill and involves substantial physical effort when continued throughout a day's work. It is therefore important to make 30 other conditions as easy as possible for the operator. One of the desirable conditions is freedom to stand squarely and firmly upon both feet. It has been found in practice that a substantial degree of fatigue results from 35 the use of the invention of said patent and the practical value of that invention is substantially reduced by reason of the fact that while using one of the speeds provided for, the operator must stand on the heel only of 40 one foot to maintain the treadle in a mid position.

It is the specific object of this invention to overcome this difficulty by providing a firm and complete rest for the operator's treadle controlling foot in all positions of 45 the treadle.

More broadly, it is an object of this invention to improve speed governing mechanism generally wherever the invention can be applied.

The several features of the invention will 50 be explained in connection with the accompanying drawings showing a plurality of embodiments thereof and then the generic invention, together with one species thereof

will be pointed out in the claims, the right 55 being reserved to cover the other forms specifically in separate applications.

Figure 1 is a side elevation of the lower portion of a lasting machine of the hand method type such as shown in said patent 60 and equipped with the variable speed mechanism which forms the subject-matter of that patent, together with a treadle stop made in accordance with this invention; Fig. 2 is a side elevation showing a preferred embodiment of this invention; Figs. 3 and 4 are perspective views showing inoperative and operative positions respectively of the treadle stop shown in Fig. 2; Fig. 5 shows a third embodiment of the invention 70 comprising a treadle with two foot plates arranged at different distances from the floor; Fig. 6 is a perspective view of the treadle controller shown in Fig. 1 and governed by the knee of the operator; Fig. 7 is 75 a diagrammatic view indicating the lateral displacement of the speed controller effected by partial and by full depressions of the 80 treadle.

The shaft 2 having the fast pulley 4 80 turned continuously by belt 5 and having the fast clutch element 6 is the driver and operates through loose pulleys 8 and 10, which alternatively coöperate with the fast clutch element 6, to actuate the large or the 85 small pulleys 12 and 14 for turning shaft 15 to operate the gripper and the tacker of the 90 lasting apparatus. The clutch element 6 normally occupies the central relation to pulleys 8 and 10 which is shown in Fig. 1 95 and this position is maintained by force transmitted through the lever 16 pivoted on the link 17, through the treadle rod 18 and the treadle 20 from the spring 22 that extends from the treadle to the frame and 100 holds the treadle uplifted. These parts are or may be all as described in said patent.

In the form shown in Figs. 1 and 6 a 105 treadle stop 25, comprising a hook to extend under and into supporting engagement with the treadle foot plate, is adjustably attached to a lever 26 pivotally connected with the machine column at 27 and having its upper end in the path of a second lever 28 that extends into the knee fork 30 in which the 110 operator rests the knee of the leg by which he stands on the treadle 20. Inward pressure by the knee swings the stop 25 under

the treadle 20 from which position it is withdrawn by spring 32 when pressure is relieved.

In the construction shown in Figs. 2, 3 and 4 a treadle stop 35 is pivoted between ears 36 on one lateral side of the treadle foot plate and is held by a spring 38 in the position shown in Fig. 3 and in full lines in Fig. 2. The stop 35 has an arm which extends inwardly and is inclined upwardly over the foot plate of the treadle in position for the operator conveniently to engage and swing the arm upwardly and the body of the stop downwardly to engage the floor by a pivotal movement of the forepart of the foot which is on the treadle while his weight continues to rest upon the heel of that foot. This provides the most convenient actuation of the treadle stop which I have yet devised. The mid position of the treadle is conveniently the one first used and the operator very readily swings the stop 35 to operative position, Fig. 4 and dotted lines Fig. 2, for affording a rigid rest for the treadle 20 and the foot that is on the treadle while the mid position is used. When full depression of the treadle is desired a relief of the pressure on the treadle allows the spring 38 to turn the stop 35 up as in Fig. 3 and full lines in Fig. 2 after which the treadle can be fully depressed.

In Fig. 5 is shown an embodiment of the invention in which the treadle 20 has a second foot plate 45 on a lever 46, pivoted at 48 on the fulcrum rod for the treadle, which engages a lateral stud 50 on the treadle lever. The foot plate 45 of the lever 46 is lower than the treadle foot plate 20 so that when foot plate 45 is depressed to the floor the treadle 20 is in its mid position. By later shifting the foot laterally to the treadle 20 said treadle may be fully depressed to the floor, the stud 50 being then lifted from the lever 46.

As I am advised it is new with me to provide a driver and driven devices adapted to be operated at different speeds from the driver, and a treadle to control the speed by its position; in combination with means, adapted to be rendered operative or inoperative by any part of that limb of the operator which manipulates the treadle, to provide a firm support for the treadle in a mid position of the treadle, the term "limb" being used in its generic sense to include any of the parts of the leg or foot.

Having explained the nature of this invention and fully described how it may be used, I claim as new and desire to secure by Letters Patent of the United States:

1. In mechanism of the class described, a driver and driven devices adapted to be operated at different speeds from the driver and speed controlling mechanism including a treadle to control the speed by its posi-

tion, means adapted to be rendered operative or inoperative by the limb, substantially as described, of the operator that manipulates the treadle to provide a firm support for the treadle in a mid position of the treadle.

2. In mechanism of the class described, a driver and driven devices adapted to be operated at different speeds from the driver and speed controlling mechanism including a treadle to control the speed by its position, a treadle stop adapted to be controlled by the treadle depressing limb of the operator to present a rigid abutment against complete depression of the treadle.

3. In mechanism of the class described, a driver and driven devices adapted to be operated at different speeds from the driver and speed controlling mechanism including a treadle to control the speed by its position, a treadle stop normally held automatically in an inoperative position and adapted to be moved manually into position to cause the treadle to present a firm rest for the operator's foot while the treadle is in less than its fully depressed position.

4. In mechanism of the class described, a driver and driven devices adapted to be operated at different speeds from the driver and speed controlling mechanism including a treadle to control the speed by its position, a pivoted treadle stop adapted to be swung into position to cause the treadle to afford a rigid support for the operator's foot while the treadle is partially depressed.

5. In mechanism of the class described, a driver and driven devices adapted to be operated at different speeds from the driver and speed controlling mechanism including a treadle to control the speed by its position, a treadle stop pivoted to the treadle and adapted to be turned by the operator's foot into position to form a rigid abutment between the treadle and the floor for the purpose described.

6. In mechanism of the class described, a driver and driven devices adapted to be operated at different speeds from the driver and speed controlling mechanism including a treadle to control the speed by its position, a treadle stop pivoted to the side of the treadle and adapted to be turned down by a lateral movement of the forepart of the operator's foot while the heel of the foot rests on the floor.

7. In mechanism of the class described, a driver and driven devices adapted to be operated at different speeds from the driver and speed controlling mechanism including a treadle to control the speed by its position, means adapted to be positioned by the operator to afford a firm rest for the foot bearing on the treadle while the treadle is in a partially depressed position, and adapted automatically to move for permitting

full depression of the treadle when treadle pressure is momentarily relieved.

8. In mechanism of the class described, a driver and driven devices adapted to be operated at different speeds from the driver and speed controlling mechanism including a treadle to control the speed by its position, a treadle stop pivoted to one side of the treadle foot plate and having a body portion adapted to be turned down to extend from the treadle to the floor and sup-

port the treadle and an arm adapted to be engaged by a lateral movement of the foot that is on the treadle to turn the said body portion of the stop.

15 In testimony whereof I have signed my name to this specification in the presence of two subscribing witnesses.

MATTHIAS BROCK.
